UNITED STATES PATENT OFFICE.

HENRY BOOT, OF PHILADELPHIA, PENNSYLVANIA, ASSIGNOR TO THOMAS DOLAN, OF SAME PLACE.

DESIGN FOR SHAWL-PATTERN.

Specification forming part of Design No. 5,496, dated January 30, 1872.

Specification describing a Design for Shawl-Patterns, produced or invented by HENRY BOOT, of Philadelphia, Pennsylvania.

The main characteristic of my design is illustrated by the diagram, Figure 1; Fig. 2 showing the application of the design to a shawl fabric.

In the present instance, the shawl fabric has two main patterns, A and B, the former consisting of a series of stripes, *b*, *c*, *d*, *e*, *f*, *g*, and *h*, all bounded by peculiar zigzag edges, the pattern B consisting of stripes similarly bounded. This zigzag edging, which is the prominent feature throughout, and which constitutes my design, is shown by plain lines in Fig. 1, and consists of two small and adjoining pointed projections alternating with a larger projection, thus forming a peculiarly-shaped denticated edging, which pervades the whole pattern.

It is immaterial, in carrying out my design, how wide or how numerous the stripes of the pattern may be, or how they are disposed of as regards position or color; but it is essential that the denticated edging should appear throughout, for it is this edging by which the desired peculiar effect is produced.

I claim as my invention—

A design for a shawl-pattern in which the patterns or stripes are defined by the denticated edging illustrated and described.

In testimony whereof I have signed my name to this specification in the presence of two subscribing witnesses.

HENRY BOOT.
